UNITED STATES PATENT OFFICE.

BERT RANDOLPH MAXWELL, OF FAIRBURY, ILLINOIS.

DESIGN FOR A DOLL.

52,334.

Specification for Design.

Patented Aug. 27, 1918.

Application filed January 16, 1918. Serial No. 212,143. Term of patent 7 years.

To all whom it may concern:

Be it known that I, BERT RANDOLPH MAXWELL, a citizen of the United States of America, residing at Fairbury, in the county of Livingston and State of Illinois, have invented a new, original, and ornamental Design for a Doll, of which the following is a specification, reference being had to the accompanying drawing, forming a part hereof.

Fig. 2 is a perspective taken from a viewpoint opposite that employed in Fig. 1.

I claim—

The ornamental design for a doll as shown.

BERT RANDOLPH MAXWELL. [L. S.]
